UNITED STATES PATENT OFFICE.

ANDREW McLEAN MOFFAT, OF FRANKFORT, KENTUCKY.

CANTEEN.

1,047,681.

Specification of Letters Patent. Patented Dec. 17, 1912.

Application filed February 12, 1912. Serial No. 677,173.

To all whom it may concern:

Be it known that I, ANDREW McLEAN MOFFAT, a subject of the King of Great Britain, residing at the city of Frankfort, in the county of Franklin, in the State of Kentucky, in the United States of America, have invented a new and useful Improvement in Canteens, of which the following is a specification.

10 The invention relates to improvements in canteens and the like as described in the present specification and illustrated in the accompanying drawings that form part of the same.

15 The invention consists essentially in the novel construction and arrangement of parts whereby a drinking cup is stowed away inside the canteen when not in use.

20 The objects of the invention, are to provide a canteen or like vessel with a drinking cup of a large holding capacity, to support the said cup rigidly inside the vessel so that it will not rattle or become detached from the vessel when being carried about, and 25 generally to provide a light and serviceable canteen in every respect with cheapness of cost and simplicity of construction.

25 In the accompanying drawings, Figure 1 is a vertical section through a canteen according to this invention. Fig. 2 is a perspective view showing the drinking cup and cap detached from the canteen with portions of the latter two elements broken away. Fig. 3, is a perspective detail of the drinking cup with a portion of the lower end broken away to disclose the interior.

Like numerals of reference indicate corresponding parts in each figure.

Referring to the drawings, 1 is the vessel 40 or body portion of the canteen of any suitable shape but here shown as the well known drum shape, said vessel having the neck 2 externally threaded at 3.

45 4 is the drinking cup comprising a tubular body portion open at each end and having the externally threaded base 5. The body portion 4 is preferably cylindrical in shape and of a diameter to nicely fit the passage 6 through neck 2, said body portion meeting the base 5 in a shoulder 7 which latter is adapted to abut the outer end of the neck 2. The threads on the base 5 are of exactly the same pitch as the threads on the neck 2, and when the cup 4 is in position within the vessel the latter threads are in vertical aline-

ment with the threads 3 and form a continuation thereof.

8 is a cap or closure comprising a simple shell whose side wall is of sufficient length to inclose the base 5 and neck 2. The side 60 wall of said cap is provided with the internal threads 9 adapted to engage the threads on the base 5 and the threads 3 on the neck and when screwed down into position, its bottom 10 abuts and forms a closure to the 65 base end of the cup 4.

11 is a small tongue extending from the shoulder 7 at a point in its circumference and adapted to engage a notch 12 in the outer end of the neck 2. The tongue 11 and 70 corresponding notch 12 may be V shaped or any other desirable shape and are provided to prevent the cup 4 rotating within the neck 2 while screwing on the cap 8, but I wish it to be understood that other means 75 if necessary may be provided for the same purpose.

13 is a cup handle comprising a springy strip of metal hinged at one end to a cross pin 14 adjacent to the mouth of the cup 4. 80

In Fig. 1 the handle is shown out of use thrown over and sprung inside the cup 4, but in Fig. 3 the said handle is shown out of the cup into a useful position for drinking, in which position the heel 15 abuts the side 85 of the cup.

I do not desire to claim the handle arrangement herein described as the same forms no part of the present invention except as a useful adjunct to the cup 4. 90

100 In the use of this invention assuming the vessel has been filled with liquid and it is desired to obtain a drink therefrom it is only necessary to unscrew the cap 8 from the threads 3, and base 5, and the cup can 95 then be withdrawn and used to receive liquid from the vessel for drinking purposes in which case the cap is replaced on the base 5, and the handle 13 is thrown over to the position as shown in Fig. 3 or the drink may be obtained directly from the vessel. In closing the vessel again the cap 8 is withdrawn from the base 3 and the cup 4 inserted through the passage 6 quite freely, for there will be no trapped air in the cup on account of its base end being opened by the removal of the cap 8. The cap is then screwed home that is to say until it embraces both the threads 3 and the threads on the base 5. In this closed position it will 110

be seen that the cup is held perfectly rigid so that there will be no rattling while the canteen is being carried about.

5 In filling the vessel 1 it is not necessary to withdraw the cup as the cap alone may be removed and the liquid inserted into the vessel by way of the cup.

An important feature of the present invention is that the neck of the vessel can 10 be made extremely large thus facilitating filling thereof and drinking therefrom. Furthermore the cup is kept free from the contaminating dust and the like by reason of its being inclosed in the vessel. I also wish 15 it to be noted that with the construction of cup herein described it is possible to use a handle, which as far as I am aware is a novel and useful feature. The device is extremely simple in construction and 20 there are no loose chains, straps or the like necessary to hold the cup in position.

I wish it to be understood that the construction herein described may be varied as 25 may become necessary so long as the essential features are adhered to as claimed in the following claims for novelty.

In canteens at present in use it is impossible to thoroughly clean the interior but 30 with the present invention, owing to the large mouth of the vessel the interior may be thoroughly cleaned by the insertion of a brush or other cleaning device.

What I claim as my invention is.

1. In a canteen or the like, the combination with a vessel having a mouth portion, of a drinking cup having a removable bottom and detachably held to said mouth portion and extending within the vessel.

2. In a canteen or the like, a combination 40 with a vessel having a mouth portion, of a drinking cup detachably held to said mouth portion and extending within the vessel, said cup having a handle housed within the cup.

45 3. In a canteen or the like, the combina-

tion with a vessel having a neck portion, of a drinking cup adapted to be stored inside the vessel and engaging said neck portion at one end, said cup having a removable bottom also engaging said neck portion. 50

4. In a canteen or the like, the combination with a vessel having a neck portion, of a movable bottomed drinking cup extending inverted into said vessel and having a shoulder abutting the outer edge of said neck, and 55 means for detachably securing the outer end of said cup to the neck.

5. In a canteen or the like, the combination with a vessel having a neck portion, of a drinking cup adapted to extend into 60 the vessel, said cup having a removable bottom adapted to engage said neck and form a closure to the vessel.

6. In a canteen or the like, a vessel having an externally threaded neck, a tubular 65 drinking cup extending inverted into the vessel through said neck and having a shoulder abutting the outer end of said neck, and a cap forming a removable bottom to said cup and threaded thereonto and 70 having a thread engaging said thread on the neck.

7. In a canteen or the like, a vessel having an externally threaded base neck, a tubular drinking cup extending into the vessel and 75 having an externally threaded end of corresponding diameter and pitch to the threads on said neck, said end joining the body part in a shoulder abutting the outer end of said neck, means for preventing rotation of the 80 cup within the neck and a cap forming a removable bottom to said cup and having an internal thread embracing said cup threads and neck threads.

Signed at Toronto, Canada, this 8th day 85 of February 1912.

ANDREW MCLEAN MOFFAT.
